UNITED STATES PATENT OFFICE

2,618,527

REFRIGERATOR CABINET

John S. Palmer, Evansville, Ind., assignor to International Harvester Company, a corporation of New Jersey

Application September 27, 1947, Serial No. 776,435

1 Claim. (Cl. 312—236)

1

This invention relates to a refrigerator cabinet and more particularly to a cabinet of the chest-type.

Most refrigerator cabinets of the household or upright type include at least two compartments, one of which is a refrigerated food storage compartment and the other of which is a non-refrigerated compartment providing space for the housing of refrigeration machinery. In cabinets of this type the machinery compartment is ordinarily closed by a tilting door which has associated therewith a vegetable bin which will be disposed within the machinery compartment when the door is closed.

Refrigerators of the chest-type are ordinarily constructed on the same principle in some respects as household or upright types, except that the former are horizontally rather than vertically elongated and the machinery compartment is alongside the food storage compartment. It is with this type of refrigeration apparatus that the present invention is primarily concerned, and it is proposed to provide an improved refrigerator cabinet construction including a common base which carries both the food compartment and the non-refrigerated and machinery compartment. It is likewise proposed to provide in the machinery compartment a dry storage or non-refrigerated space for the purpose of storing articles for which refrigeration is not necessary. To this end the invention is directed toward the provision of modified forms of refrigerator cabinet constructions utilizing to the greatest extent possible the non-refrigerated space occupied in part by the refrigeration machinery and to equip this space with a partition in the form of a shelf so that a storage space is provided apart from either the food compartment or the machinery compartment.

Other objects of the invention include: an improved refrigerator cabinet construction in which the food compartment and non-refrigerated compartment are provided as separate structures associated together on a common base; to provide a removable shelf in the non-refrigerated space; and to provide various forms of cover or door structures for the dry storage or non-refrigerated space.

Other objects and features inherent in and encompassed by the invention will become apparent from a reading of the ensuing description of preferred embodiments of the invention as illustrated in the accompanying sheets of drawings in which:

Figure 1 is a front view partly in section of one form of the invention;

5
10

Figure 2 is a perspective view of the same construction, a portion of the cabinet being broken away to illustrate the interior of the non-refrigerated space;

5
15

Figure 3 is a view similar to Figure 2 but showing a form of the invention in which the cover is arranged in a different manner; and

Figure 4 is a perspective view of a further modified form of the invention.

Figures 1 and 2

The refrigerator cabinet here shown includes an elongated rectangular base 10 which carries thereabove a box-like structure 11 including a plurality of vertically insulated walls to provide a food compartment 12 having an access opening at the top thereof as at 13 closed by a hinged cover or door 14.

That portion of Figure 1 that is broken away in section shows by way of example the manner in which the box-like structure 11 may be constructed. The food compartment has at its right-hand end (as viewed in Figure 1) a vertical end wall 15 provided by a pair of spaced apart inner and outer sheets 16 and 17. The food compartment also includes a bottom insulated wall 18. The compartment is cooled or refrigerated by a plurality of evaporator coils 19 which surround the inner sheet 16 and by a further series of evaporator coils 20 associated with the bottom wall 18. This construction is generally conventional and forms no detailed part of the present invention.

The box or chest 11 that includes the food compartment 12 occupies a major portion of the base 10 and at one end the base projects beyond the end wall 15 in the form of an integral base extension 21. A second box-like structure 22 having an end wall 23 and a front wall 24 is supported on the base extension 21 and is detachably associated therewith and with the end wall 15. The proximate face of the structure 22 is preferably opened and flanged as at 25. This flange is preferably detachably secured to the end wall 15. The wall 15 is thus common to both the food compartment 12 and the non-refrigerated space within the structure 22, which space is divided into upper and lower compartments 26 and 27 by means of a partition in the form of a transverse shelf 28. The space is open at its top as at 29 (Figure 2) and this opening is normally closed by a hinged cover 30. In this form of the invention the cover 30 is hinged at the rear upper edge of the structure 22.

The structure 22 includes a bottom 31 (Figure 55 1) which is located on a plurality of pins 32 pro-

jecting upwardly from the base extension 21. The lower compartment 27 is adapted to house refrigeration machinery indicated generally by the numeral 33 (Figure 2), which machinery includes a conventional condenser 34. The front wall 24 of the structure 22 includes a grilled opening 35 in front of the condenser 34 by means of which air may circulate through the lower or machinery compartment 27.

The shelf 28 is preferably removably carried in the non-refrigerated space by means of a pair of angles 36. The cover 30 for the non-refrigerated space and the cover 14 for the food compartment 12 are, in this form of the invention, co-planar, thus lending to the attractive appearance of the chest. Likewise both covers provide access to both compartments from the top. The shelf 28 provides in effect a bottom wall for the upper compartment 28, which compartment may be used for the storage of articles for which refrigeration is not necessary. Inasmuch as it is seldom that access must be had to the machinery compartment 27, the division between the two compartments by the shelf 28 affords an upper compartment of greater utility to access to which may be had by opening the cover 30. When it is necessary to gain access to the machinery compartment 37, the shelf 28 may be removed upwardly through the opening 29 when the cover 30 is opened.

Figure 3

The form of the invention shown in Figure 3 follows closely that just described, only in this instance the structure 22 includes a cover 37 that is hinged on an axis lying along the upper edge of the end wall 23. An upper portion of the front wall 24 is recessed as at 38 to provide for easier gripping of the cover 37 for opening the cover. The structural and functional advantages of this form of the invention are comparable to those set forth in connection with those set forth in Figures 1 and 2.

Figure 4

In this form of the invention the structure 22 may be permanently closed at its top by a cover 39 which is co-planar with the cover 14 for the food compartment 12. The box-like structure 22 is opened at its front as at 40 and this opening is normally closed by a hinged door 41 having in the lower portion thereof a grilled opening 42 in alignment with the condenser 34 in the lower or machinery compartment 27. Otherwise the structural and functional characteristics of this form of the invention are the same as those set forth in connection with the modifications set forth above.

SUMMARY

In all forms of the invention the primary feature is the utilization of non-refrigerated space for the purpose of providing an additional storage compartment. This storage compartment is so arranged with respect to the other components of the cabinet as to be readily accessible and convenient to use. In all instances the shelf 28 may be readily removed for the purpose of gaining access to the refrigeration machinery.

The embodiments of the invention chosen for the purposes of illustration and description here-

in are those preferred as the result of selective tests based upon requirements for achieving the objects of the invention and developing the utility thereof in the most desirable manner, due regard being had to existing factors of economy, simplicity of design and construction, production methods and the improvements sought to be effected. It will be appreciated, therefore, that the particular structural and functional aspects emphasized here are not intended to exclude, but rather to suggest, such other adaptations and modifications of the invention as fall within the spirit and scope of the invention as defined in the appended claim.

15 What is claimed is:

A refrigerator cabinet of the chest type, comprising: a first structure including a bottom wall and vertical side and end walls defining an open-top compartment to be refrigerated; a second structure including a vertical side wall and a vertical end wall, both of substantially the same height as the first structure walls; flange means on said second structure for detachably securing the second structure at one end of the first structure with the second structure side wall providing an aligned extension of one of the first structure side walls and the proximate end wall of the first structure serving as another wall of the second structure to define an open-top non-refrigerated space; a base support disposed so as to extend beneath both of said first and second structures; a horizontal shelf removably positioned on flange-like supports within the non-refrigerated space and disposed so as to separate said space into an upper dry-storage compartment and a lower refrigeration machinery compartment, and having said shelf removable upwardly through the open-top of said non-refrigerated space so as to afford access to said machinery compartment; said side wall of said second structure being provided with a gridded opening communicating with said refrigeration machinery compartment; a first cover structure for the top-opening of said refrigerated compartment mounted for movement to open and close said opening; a second cover structure for the top-opening of said non-refrigerated space; said covers being co-planar with the pivotal axes of both horizontally disposed and in axial alignment; and having said covers arranged so that when both are in a closed or in a fully opened position with regard to their respective openings the outer surfaces of said cover structures will be substantially co-extensive and in alignment one with the other.

55 JOHN S. PALMER.
